ATTORNEY

UNITED STATES PATENT OFFICE.

STEVEN GENCHY, OF NEW YORK, N. Y.

EYE DUST-REMOVING INSTRUMENT.

Application filed March 24, 1927. Serial No. 178,112.

This invention relates to a new and useful device in the nature of an eye dust removing device particularly adapted for removing dust, dirt, foreign matter, and the like, 5 from the eye of a person.

The object of the invention is to provide an eye dust removing device of novel construction and arrangement of parts, herein-after more fully described, claimed, and 10 illustrated in the accompanying drawing.

Fig. 1 is a side elevational view of my improved device, as same would appear when in use.

Fig. 2 is a front elevational view thereof.

Fig. 3 is a similar view to that shown in Fig. 1 illustrating a modification of my improved device.

Fig. 4 is a similar view illustrating a fur- 15 ther development thereof.

Fig. 5 is a fragmentary sectional view, taken on the line 5—5 of Fig. 4.

As here embodied my improved device comprises a tubular member 10, provided with an eye piece 11, attached thereto, at one 25 extremity. The ring shaped member 12, is adapted to engage over the other extremity of the tubular member 10, and is secured thereto. The ring shaped member 12, is provided with lug elements 13 and 14, pro- 30 vided with apertures adapted to receive the tubes 15 and 16, attached thereto, and extended therefrom. The threaded members 17 and 18, thumb screws, set screws, or the like, are threadedly attached to the lug ele- 35 ments 13 and 14 and to the tubes 15 and 16, respectively, as a means of securing, a horse- hair 19, or the like thereto, the said horse- hair 19 being extended through the tubes 15 and 16, so as to form a loop, as clearly shown 40 in Fig. 2. The magnifying glass 20, is positioned in the tubular member 10.

The above described construction being such as will permit my improved device to be held in front of the eye 21 of a per- 45 son enabling the said person to look through my improved device, and draw the horse- hair 19, over the eye 22, of a second person, as a means of removing dust, dirt, for- 50 eign matter, or the like from the eye 22 of the second person.

The ring shaped members 23 and 24, are 55 rotatively mounted on the tubular member 10, so as to be frictionally held thereon in any desired position. The ring shaped mem-

similar shaped members 25 and 26, attached thereto, at or near one extremity thereof. The above described construction being such as will permit the above mentioned horse-hair 19 to be adjustably positioned, as may 60 be required to enable the above referred to dust or dirt to be removed from the eye of a person, as above set forth.

In Figs. 4 and 5, of the accompanying drawing, I have shown a supporting member 65 30, a cap member 31, attached thereto, said supporting member 30 and said cap member 31, adapted to rotatively engage the tubular member 10 and positioned intermediate the eye piece 11 and a ring shaped member 32, 70 attached to one extremity of the tubular member 10.

The supporting member 30, is provided with lug elements 33 and 34, provided with apertures adapted to receive the rod 35. 75 The segment gears 36 and 37, are rotatively mounted on the rod 35. The segment gears 36 and 37, are provided with extended ele- 80 ments 38, provided with apertures adapted to receive the above mentioned tubes 15 and 16.

The pinion 39 meshes with the segment gears 36 and 37, and is attached to the rod 40, rotatively mounted on the lug elements 41 and 42, of the supporting member 30. 85 The rod 40 has attached thereto, a knob 43, handle, or the like.

The above described construction being such as will permit the above mentioned horse-hair 19, to be adjusted, as hereinbefore 90 set forth and described.

Having thus described my invention what I claim as new and desire to protect by Letters Patent of the United States is as fol- 95 lows:

1. A device of the class described comprising a supporting member, a cap member attached thereto, said supporting member and said cap member being adapted to rotatively engage a tubular member, said sup- 100 porting member being adapted to rotatively support a segment gear and a second seg- ment gear, a horse-hair attached to and ex- tended therefrom, a pinion engaging the said segment gears, said pinion being mounted on a rod rotatively supported by the said supporting member, and a knob attached to the said rod.

2. A device of the class described com- 105 prising a supporting member, a cap mem-

ber attached thereto, said supporting and cap members being adapted to rotatively engage a tubular member, said supporting member being adapted to rotatively support a segment gear and a second segment gear, said segment gears being provided with extended elements, a horse-hair adjustably attached to and extended therefrom, a pinion

engaging the said segment gears, said pinion being mounted on a rod rotatively supported by the said supporting member, and a knob attached to the said rod. 10

In testimony whereof I have affixed my signature.

STEVEN GENCHY.
